UNITED STATES PATENT OFFICE.

PAUL PHILIPSBERG AND IGNATZ PHILIPSBERG, OF BROOKLYN, NEW YORK.

SEAL-TAG.

1,303,386.

Specification of Letters Patent. Patented May 13, 1919.

Application filed March 6, 1918. Serial No. 220,725.

To all whom it may concern:

Be it known that we, PAUL PHILIPSBERG and IGNATZ PHILIPSBERG, citizens of Austria-Hungary, and residing at Brooklyn, in the county of Kings and State of New York, have invented certain new and useful Improvements in Seal-Tags, of which the following is a specification, such as will enable those skilled in the art to which it applies to make and use the same.

This invention relates to seal tags and particularly to devices of this class designed for use by merchants or other dealers in clothing or wearing apparel as a protection against fraud, and the object of this invention is to provide a tag of this class composed of a plurality of foldable parts, and means for locking said parts together when folded, a number of said parts being adapted to be passed through a part of a garment or other wearing apparel before said tag is sealed; and a further object being to provide a seal tag of the class and for the purpose specified which is simple in construction and operation and effective in use, and which is composed entirely of fibrous material.

The invention is fully disclosed in the following specification, of which the accompanying drawing forms a part, in which the separate parts of our improvements are designated by suitable reference characters in each of the views, and in which:

Figure 1 is a plan view of our improved seal tag in blank form;

Fig. 2 a view of one end portion of said tag indicating the first step in the operation of folding the same;

Figs. 3 and 4 views similar to Fig. 2 but showing the second and third steps in folding the seal tag;

Fig. 5 a view of the complete tag showing the fourth step in folding the same;

Fig. 6 a view similar to Fig. 5 but showing the fifth step of folding the tag and indicating a part of said tag passed through a button-hole in a garment;

Fig. 7 a view similar to Fig. 6 but showing the last step of folding said tag and indicating it in its sealed position and permanently secured to a garment; and,

Fig. 8 a section on the line 8—8 of Fig. 7 and on an enlarged scale.

In the drawing 10 is an approximately L-shaped blank from which our improved seal tag is formed, said blank comprising two

main body parts 11—12 divided by a score or folding line 13, the part 12 extending from the score line to the edge 14 of the blank, and at one side edge of said part 12 is another part 15 separated from the part 12 by two score or folding lines 16, and at one side of the part 15 is a flap 17 separated from the part 15 by a score or folding line 18.

The part 12, or the edge portion 14 thereof, is divided into two supplemental parts 19 and 20 by score or folding lines 21, and the part 15 is divided into three supplemental parts 22, 23 and 24 by score lines 25, 70 while the part 17 is also divided into three supplemental parts 26, 27 and 28 by score lines 29; and it will be noted that the score lines 21, 25 and 29 are in common alinement, and where the score lines 25 and 29 cross 75 the score line 18, the separate parts 15 and 17 of the blank are provided with apertures 30, and the supplemental part 23 of the part 15 is provided adjacent to the score line 18 with an elongated aperture 31. The 80 free edges of the supplemental parts 26 and 28 of the parts 17 are provided with inwardly directed angular faces 32 which join an outwardly directed V-shaped tongue 33 on the supplemental part 27.

At one side of the part 11 is a folding lock flap 34 connected with the part 11 by two score lines 35, and the free edge of the lock flap 34 is provided with a folding lip 36 which and said end portion of the lock 90 flap 34 are provided with an aperture 37. The flap 34 adjacent to the inner end thereof is cut out to form an ear 38, and said flap is provided between the ear 38 and the aperture 37 with a series of perforations 39 95 which render said lock flap breakable or rupturable under tension, as hereinafter described.

The above description clearly sets out the separate parts of our improved seal tag and the operation of folding the same for use will be readily understood on a consideration of said description in connection with the accompanying drawing and the following statement.

The part 17 is first folded inwardly on the score line 18 to bring said part onto the part 15, as clearly shown in Fig. 2, after which the separate parts 19, 22 and 26 of the parts 12, 15 and 17 are folded inwardly 110 onto the supplemental parts 20, 23 and 27, as clearly shown in Fig. 3, after which both

of said supplemental parts 19—20, 22—23 and 26—27 are folded onto the part 12 and supplemental parts 24 and 28 respectively, as clearly indicated in Fig. 4.

- 5 The part 12 with the parts 15 and 17 and the supplemental parts connected therewith are then folded backwardly onto the part 11, as clearly indicated in Fig. 5, after which the folded parts 15 and 17 and the 10 supplemental parts thereof are passed through a buttonhole or other opening 40 in a garment 41 and folded forwardly onto the part 11, as shown in Fig. 6, in which figure the lip 36 in the flap 34 is shown folded forwardly, and in order to seal said tag in the 15 position shown in Fig. 6, the lock flap 34 in its folded position as shown in said figure is passed through the aperture 31 in the supplemental part 28 until the folded lip 36 thereof engages the tongue 33 on the supplemental member 27, or until said flap has 20 reached its innermost position and cannot be withdrawn without exerting considerable pressure.
- 25 In Fig. 8 it will be noted that if it be attempted to withdraw the lock flap 34, the folded lip 36 thereof will operate in connection with the tongue 33, or said tongue will pass through the aperture 37 in said flap and prevent the withdrawal of said flap, but if sufficient force is exerted on said flap, the same will be broken or ruptured along the perforated lines 39, as will be readily understood. By providing the ear 30 38 on the flap 34 which as will be clearly seen on a consideration of Fig. 7 operates in connection with one side wall of the aperture 31, an accidental pull or strain on the lock flap 34 will be taken up by said ear and 35 prevent the rupture or breaking of the flap 34 on the perforated lines 39.

It will be noted that our improved seal tag, or that part thereof which passes through the buttonhole or other opening in the garment 41, is of three thicknesses as 40 clearly shown in Fig. 8, or consists of the supplemental parts 22, 23 and 24 which will make the connection of the tag with the garment strong and durable and prevent the 45 accidental tearing of said tag when in use, especially when said tag is composed of strong manila paper, or of other strong fibrous material, and various changes in and modifications of the details of construction 50 of our improved seal tag, as herein shown and described, may be made, within the scope of the appended claims, without departing from the spirit of our invention or 55 sacrificing its advantages.

60 Having fully described our invention, what we claim as new and desire to secure by Letters Patent, is:—

1. A seal tag composed of a plurality of foldable parts, a number of said folded 65 parts being adapted to be passed through a

part of a garment, and means for interlocking said number of folded parts with another part of said tag to seal the same.

2. A seal tag composed of a plurality of foldable parts, a number of said folded parts being adapted to be passed through a part of a garment, and means for interlocking said number of folded parts with another part of said tag to seal the same, said last named part of the tag being provided with a plurality of perforations.

3. A seal tag composed of a plurality of foldable parts, a number of said folded parts being adapted to be passed through a part of a garment, one of said folded parts being provided with an aperture, and said tag being provided with another part adapted to be passed through the aperture in said first named folded parts to seal the separate parts of said tag together.

4. A seal tag composed of a plurality of foldable parts, a number of said folded parts being adapted to be passed through a part of a garment, one of said folded parts being provided with an aperture, another of said folded parts being provided with a tongue and said tag being provided with another part adapted to be passed through the aperture in said first named folded parts and to engage said tongue to seal said tag.

5. A seal tag composed of a plurality of foldable parts, a number of said folded parts being adapted to be passed through a part of a garment, one of said folded parts being provided with an aperture, another of said folded parts being provided with a tongue, said tag being provided with another part adapted to be passed through the aperture in said first named folded parts and to engage said tongue to seal said tag, and said last named part being provided with perforations.

6. A seal tag composed of a plurality of foldable parts, a number of said folded parts being adapted to be passed through a part of a garment, one of said folded parts being provided with an aperture, another of said folded parts being provided with a tongue, said tag being provided with a part having a foldable lip member, and said part being adapted to be passed through the aperture of said first named folded parts to bring said foldable lip member into operative connection with said tongue on one of said first named folded parts to seal the separate parts of the tag together.

7. A seal tag composed of a plurality of foldable parts, a number of said folded parts being adapted to be passed through a part of a garment, one of said folded parts being provided with an aperture, another of said folded parts being provided with a tongue, said tag being provided with a part having a foldable lip member, and said part being adapted to be passed through the

aperture of said first named folded parts to bring said foldable lip member into operative connection with said tongue on one of said first named folded parts to seal the 5 separate parts of the tag together, and said last named part of the tag being provided with an ear adapted to operate in connection with the aperture in said first named folded parts.

10 8. A seal tag composed of a plurality of foldable parts, a number of said folded parts being adapted to be passed through a part of a garment one of said folded parts being provided with an aperture, another 15 of said folded parts being provided with a tongue, said tag being provided with a flap the edge portions of which is provided with an aperture, said flap being adapted to be passed through the aperture in said first 20 named folded parts to bring the aperture in said flap into operative connection with the tongue on one of said first named folded parts to seal the separate parts of the tag together, said flap being provided with an 25 ear adapted to operate in connection with the aperture in said first named folded parts, and said flap being provided between the aperture therein and said ear with perforations.

30 9. A seal tag composed of two main body parts foldable one upon another, one of said parts being provided with a plurality of

foldable members one of which is provided with an aperture and another of which with a tongue, the other of said main body parts 35 being provided with a foldable flap which is adapted to be passed through the aperture in the folded members of the other part and engage the tongue therein to seal the separate parts of the tag together. 40

10. A seal tag composed of two main body parts foldable one upon another, one of said parts being provided with a plurality of foldable members one of which is provided with an aperture and another of which with 45 a tongue, the other of said main body parts being provided with a foldable flap the edge portion of which is provided with an aperture, said flap being adapted to be passed through the aperture in the folded members 50 of the other part to bring the aperture of said flap in operative connection with the tongue thereof to seal the separate parts of the tongue together when folded.

In testimony that we claim the foregoing 55 as our invention we have signed our names, in presence of the subscribing witnesses, this 4th day of March, 1918.

PAUL PHILIPSBERG.
IGNATZ PHILIPSBERG.
